INVENTOR

Alexander Stewart,
By his Attorney,
Wm. B. Powell

UNITED STATES PATENT OFFICE.

ALEXANDER STEWART, OF PHILADELPHIA, PENNSYLVANIA.

DESIGN FOR A BASE FOR FARINA-BOILERS.

SPECIFICATION forming part of Design No. 19,183, dated June 25, 1889.

Application filed May 13, 1889. Serial No. 310,645. Term of patent 7 years.

To all whom it may concern:

Be it known that I, ALEXANDER STEWART, a citizen of the United States, residing at Philadelphia, in the county of Philadelphia and State of Pennsylvania, have invented and produced a new and original Design for a Base for Farina Boilers, Steamers, &c., of which the following is a specification, reference being had to the accompanying drawings, forming part hereof.

Figure 1 is a side elevation of a base, showing my design, and Fig. 2 is a plan view of the same, these two views being deemed necessary in order to fully illustrate my design.

My invention has relation to farina boilers, steamers, and similar culinary utensils, and has for its object to provide a new and original design for a base for the same.

Heretofore bases for the above-mentioned utensils have been generally made in the form of a frustum of a cone, or tapering from their bottom to their top edges. The leading feature of my design is the provision of a base substantially in the form of an oblate spheroid, having around its center or midway between its flattened poles an annular tapered bead, which is rounded at its apex. The portions of said base contiguous to said bead are slightly curved outwardly to meet the inner edge of the bead, said base also having an annular segmental rim encircling the opening in the top or around the upper flattened portion, and the edge of its lower flattened portion rounded and the portion of the base contiguous thereto curved or slightly concaved, the two forming an ogee or wave-like bottom. Said base also is provided with any suitable form of handle.

All of which features will be more specifically described hereinafter, and are clearly shown in the drawings, wherein—

A represents the oblate spheroidal base or pan, having the round portions a a' and the flattened ends a^2 a^3 , also having midway between said flattened portions the annular rim

B , which tapers from the point of its junction with the slight outward curvatures a^4 a^5 of the base A and has its apex rounded, as shown at b . The opening C or the upper termination a^6 of the curved portion a is encircled by the annular rim c , which is segmental or almost circular in cross-section and joins the said curved portion a . The lower flattened portion a^3 of the base A has its edge rounded, as shown at d , which rounded portion joins the curve or concavity d' of the said base, which concavity joins the round portion a' , said round portion d and the curve d' forming jointly an ogee bottom for the round portion a' of the base A , or a rim for the flattened end a^3 of said base.

As shown in Fig. 1 of the drawings, the base or pan A is provided with the usual handle D , which does not in itself involve any particular design. Therefore I do not wish to be understood as limiting myself to any peculiar shape or form of handle.

What I claim, and desire to secure by Letters Patent, is—

The design for a base for culinary boilers and steamers, consisting of an oblate spheroidal pan A , provided with a handle and having rounded portions a a' and flattened ends a^2 a^3 , the portion a having its opening C encircled by an annular segmental rim c , joining the upper part a^6 of said round portion, and the portion a' having a rounded edge d joining the concavity d' of said portion, said pan A also having the annular tapering bead b , with the rounded apex b' midway between its ends a^2 a^3 , as shown and described.

In testimony whereof I have hereunto set my hand, at the city of Philadelphia, Pennsylvania, this 6th day of May, A. D. 1889.

ALEXANDER STEWART.
